ATTORNEY

UNITED STATES PATENT OFFICE

PHILIP J. MARTIN, OF ELIZABETH, NEW JERSEY

CABLE GRIP

Application filed April 17, 1929. Serial No. 355,813.

The invention relates to improvements in woven cable grips and has to do primarily with providing an armor or protection for the draft end of such a cable grip.

5 Cable grips of the character described and illustrated in the present application are well known in the art and consist of a plurality of strands of wire or wire cord woven into an open mesh hollow body, cylindrically shaped 10 and with means at one end for attaching a draw rope. It is also a well known fact that the eye and shoulder portions of such grips are subjected to great strains as they are being drawn through the ducts and when such 15 parts of the grip are left unprotected, they wear out quickly and the grip becomes useless. Different means have been devised in the art for protecting the grips. The pairs of strands adjacent the shoulder portions of 20 the grip have been inclosed by individual tubes. However, this has its disadvantages in that the tubes soon wear out and the wire is exposed and the tubes interfere with the flexibility of the grip. Leather protectors 25 laced about the shoulder portions of the grip have been used. While these leather protectors do not interfere in any great degree with the flexibility of the cable grip, they are very short lived as, frequently, drawing the 30 cable through one duct will destroy them.

The principal object of the present invention is to provide an armor that will overcome the foregoing objections and one that will give a maximum amount of protection to the 35 eye portion and shoulder portion of the grip and at the same time not impair in any manner the flexibility of the grip.

A further object is to provide an armor that may be readily and quickly installed on 40 a cable grip so that when one set is worn out or distorted too much, a new set may be placed on the cable grip.

A further object is to provide an armor which is exceedingly simple in construction 45 and thereby cheap to manufacture so that no great loss is entailed when a set of armor is discarded.

Further objects will become apparent as 50 this specification proceeds. Referring to the drawings forming a part thereof, and in

which a preferred embodiment of the invention is illustrated:

Fig. 1 is an elevational view of the draft end of a cable with the armor or protection applied thereto, one of the protecting members being in elevation and the other in section;

Fig. 2 is a cross sectional view through the shoulder portion of the grip and armor and is taken on line 2—2 of Fig. 1;

Fig. 3 is a cross sectional view through the neck portion and is taken on line 3—3 of Fig. 1; and

Figs. 4 and 5 are cross sectional views taken on lines 4—4 and 5—5 of the eye portion of the grip.

Referring again to said drawings, the reference numeral 6 designates the interchangeable woven open mesh grip. Grips of this general type being well known, suffice it to say the grip is formed of a plurality of strands of wire or wire cord 7 which are woven into an open mesh hollow body, cylindrically shaped. The gripping action of these grips is due to the change of form of 75 the meshes. When a pull is exerted the meshes are elongated axially and are narrowed circumferentially, thus decreasing the diameter of the grip and causing it to firmly grasp the cable. The grip may be of any 80 desired length and in Fig. 1 a substantial part of the body portion of the grip is broken away.

At the draft end of the cable grip the strands 7 are brought together so as to form 85 a shoulder portion 8 and neck portion 9. As indicated at 10 in Fig. 1 the neck portion may be served with marline or other suitable material. The strands are then brought around a thimble 11 so as to form a rigid eye 12 to 90 which the draw rope is attached.

In drawing a cable through the duct, due to irregularities in the duct, a great strain is put on the exposed strands in the eye portion and on the shoulder portion of the grip as 95 these portions come in contact with the irregularities. As heretofore stated the object of the present invention is to provide a simple means for protection of these parts.

For this purpose a pair of rigid members 100

adapted to substantially conform to the contour of the eye portion, neck portion and shoulder portion of the grip is provided. These members are preferably formed of sheet metal and may be duplicates of each other.

Their lower parts 13 substantially enclose the shoulder portion 8 of the cable grip and their edges are in overlapping relation to each other. Their intermediate parts 14 which enclose the neck portion 9 also have their edges overlapped. The neck portions 14 are preferably provided with corrugations 15 about which a wire 16 may be wrapped to secure the members in position on the cable grip.

The portions 17 of the protection members are substantially semi-circular in cross section as shown in Figs. 4 and 5 and embrace or enclose the exposed wires on the eye portion of the grip. The portions 17 are in overlapping relation where they meet each other as indicated at 18 in Fig. 1.

As the cable grip is being drawn through a duct the portions 17 of the armor will protect the exposed strands of the eye of the grip and the portions 13 will protect the shoulder of the grip. If the shoulder portions 13 strike an obstruction they are free to move toward each other so as not to interfere with the flexibility of the grip. As the shoulder portions 13 move toward each other, neck portions will tend to move away from each other, but this movement will not be sufficient to separate the overlapped ends 18.

The two parts of the armor may be made duplicates of each other so as to avoid the necessity of having right and left hand members or they may be made from different dies if desired. When they are made duplicates of each other there will be sufficient resiliency in the metal to allow one part to be sprung over the other at the overlapping ends 18.

The armor may be readily and quickly secured to the cable grip and when either or both of the members are worn or distorted new ones may be substituted with very little trouble and expense due to the simplicity and cheapness of manufacture of an armor of this type.

While in the preferred embodiment a pair of members is described and illustrated, it is considered to be within the scope of the invention to provide more than two members secured to the grip and conforming substantially with the contour of the shoulder portion, neck portion and eye portion of the grip and having sliding relation with each other so as not to impair the flexibility of the grip.

Changes in details of form and construction may be made by one skilled in the art without departing from the spirit of the invention or the scope of the appended claims.

What I claim is:

1. A cable grip armor for a cable grip

formed of a tubular woven mesh of wire strands bunched together at one end, said armor comprising a plurality of rigid overlapping members adapted to conform substantially to the contour of the eye portion, neck portion and shoulder portion of the cable grip to protect the eye and shoulder portions of said grip against wear when being drawn through a duct.

2. A cable grip armor for a cable grip formed of a tubular woven mesh of wire strands bunched together at one end, said armor comprising a pair of rigid overlapping members adapted to conform substantially to the contour of the eye portion, neck portion and shoulder portion of the cable grip to protect the eye and shoulder portions against wear when being drawn through a duct, and means for securing said rigid overlapping members to said cable grip.

3. A cable grip armor for a cable grip formed of a tubular woven mesh of wire strands bunched together at one end, said armor comprising a pair of rigid removable members adapted to conform substantially to the contour of the eye portion, neck portion and shoulder portion of the cable grip, said members embracing the exposed area of the eye portion and substantially enclosing the neck and shoulder portions of the grip, and means for securing said members to said cable grip.

4. A cable grip armor comprising a pair of rigid removable members adapted to conform substantially to the contour of the eye portion, neck portion and shoulder portion of the cable grip, said members embracing the exposed area of the eye portion and being in overlapping relation at the upper part of said eye portion, and substantially enclosing the neck and shoulder portions of the grip and means for securing said members to said cable grip.

5. A cable grip armor comprising a pair of rigid removable members adapted to conform substantially to the contour of the eye portion, neck portion and shoulder portion of the cable grip, said members embracing the exposed area of the eye portion and being in overlapping relation at the upper part of said eye portion, and said members substantially enclosing the neck and shoulder portions of said cable grip and being in overlapping relation to each other on said neck and shoulder portions, and means for securing said members to said cable grip.

6. A cable grip armor comprising a pair of rigid removable members adapted to conform substantially to the contour of the eye portion, neck portion and shoulder portion of the cable grip, said members embracing the exposed area of the eye portion and being in overlapping relation at the upper part of said eye portion, and said members substantially enclosing the neck and shoulder portions of said cable grip and being in overlapping re-

lation to each other on said neck and shoulder portions, and means for securing said members to said cable grip at the neck portion thereof.

- 5 7. A cable grip armor for a cable grip formed of a tubular woven mesh of wire strands bunched together at one end, said armor comprising a plurality of rigid members adapted to conform substantially to the
10 contour of the eye portion, neck portion and shoulder portion, said members being in sliding relation to each other and means for securing said members to said cable grip.

In testimony whereof I affix my signature.
